Primary Examiner — Michael C Stout*Assistant Examiner* — James T Tyree(74) *Attorney, Agent, or Firm* — Daryl R. Wright; Greg Carr(57) **CLAIM**

The ornamental design for a model vehicle platform assembly as shown and described.

DESCRIPTION

FIG. 1 is an upper, right, front perspective view of a model vehicle platform assembly showing our new design;

FIG. 2 is an upper, right, rear perspective view thereof;

FIG. 3 is a lower, left, front perspective view thereof;

FIG. 4 is a lower, left, rear perspective view thereof;

FIG. 5 is a front elevation view thereof;

FIG. 6 is a rear elevation view thereof;

FIG. 7 is an upper plan view thereof;

FIG. 8 is a lower plan view thereof;

FIG. 9 is a right-side elevation view thereof; and,

FIG. 10 is a left-side elevation view of the model vehicle platform assembly.

The broken lines depict portions of the model vehicle platform assembly that form no part of the claimed design.
